DOORKNOB SPINDLE

Eric W. Ericsson, Brooklyn, N. Y.

Application January 3, 1939, Serial No. 248,935

7 Claims. (Cl. 292—350)

This invention relates to the spindles of door knobs employed in connection with latch or lock mechanisms controlling the opening and closing of a door, and the object of the invention is to provide a spindle of the character described, at least one end portion of which is provided with an elongated bore or passage having an aperture in one wall of the spindle opening into said passage, and to the provision of a member fitting snugly in the passage and movable longitudinally thereof, having means for receiving a screw for coupling a knob with the spindle to provide accurate arrangement of the knob on the spindle to prevent rattling or loose movement of the knob in connection with the door structure; a further object being to provide a coupling member slidably engaging the bore or chamber of the spindle which is provided with a knurled or other roughened outer surface to securely retain the knob in different positions of adjustment; a further object being to provide means for keying the adjustable coupling member against rotation in said bore or chamber; a further object being to provide means retaining the coupling member against accidental displacement from said bore or chamber; a still further object being to provide an angular mounting of the coupling screw with said coupling member to provide a wedge-like clamping action between the knob and spindle so as to securely hold the screw against loosening, and with these and other objects in view the invention consists in a device of the class and for the purpose specified, which is simple in construction, efficient in use, and which is constructed as hereinafter described and claimed.

The invention is fully disclosed in the following specification of which the accompanying drawing forms a part, in which the several parts of my invention are designated by suitable reference characters in each of the views, and in which:

Fig. 1 is an edge view of a door showing one of the doorknobs and part of one of my improved spindles in section.

Fig. 2 is an enlarged sectional detail view of one end portion of a spindle made according to my invention with the knob detached.

Fig. 3 is a section on the line 3—3 of Fig. 2.

Fig. 4 is a perspective view of an adjustable coupling which I employ detached from the spindle, and

Fig. 5 is a plan view of one complete form of spindle which I employ.

In Fig. 1 of the drawing I have shown at 10 the edge view of a part of a door in which is ar-

ranged the usual latch or combination latch and lock casing 11, the latch bolt of which is indicated at 12. At both sides of the door are arranged the usual face plates or scutcheon plates 13 having cup-shaped bushings as at 14 forming 5 sockets for the inner ends of knobs 15. Each knob has a shank portion 16 apertured as seen at 17 to receive the securing screw 18. Each knob is also provided with an elongated passage 19 for the reception of the spindle 20, the latter 10 being in operative engagement with the latch 12 in the usual manner so as to withdraw the same in the operation of opening the door from either side thereof. It will also be apparent that the spindle may be of any type or kind adapting 15 it for use in connection with various types of locks and including locks where each knob independently controls the opening and closing of the door. However, as my invention relates primarily to the manner of coupling the knobs with 20 the spindles and not to any other structure of the spindle or the like, the other features of such devices are incidental and for this reason are not illustrated in detail.

It will of course be understood that both ends 25 of the spindle may be of identical construction to provide the fine and close gaged mounting of each knob on the spindle. In such instances, the brief description of one end of the spindle will of course apply to both ends thereof. However, in 30 Fig. 5 of the drawing, one possible adaptation of spindle construction is disclosed. In this illustration, one end of the spindle is provided with spaced threaded apertures 21 for receiving the screw 18 of one knob to adjust the knob into at 35 least two different positions on the spindle, whereas the other end of the spindle is of the same structure as that which I will now proceed to describe in detail.

In the construction shown, the spindle is of 40 rectangular cross sectional form, and for the purpose of economizing in the cost of constructing the same, a round bore or passage 22 is drilled or otherwise formed in the end portion of the spindle, and one side wall of said end of the 45 spindle is milled to form an elongated aperture 23 which opens into the bore or passage 22. The bore 22, including the aperture 23, will be of sufficient length to provide a wide range of adjustment of a coupling block or member 24 and the 50 doorknob 15 longitudinally of the spindle, the knob being secured to the coupling 24 through the screw 18.

The coupling 24 is made to fit snugly but freely in the bore 22 as will appear upon a considera- 55

tion of Fig. 3 of the drawing. The outer surface of the coupling is knurled or otherwise roughened as seen at 25, note Fig. 4, so as to provide tooth-like engagements with the walls of the bore 22 when the coupling 24 is clamped in position by the screw 18. The coupling 24 is also provided with a transverse threaded aperture 26 which is preferably arranged at slight inclination to the perpendicular as will appear upon a consideration of Fig. 2 of the drawing so that the screw 18 will be wedged in position and retained against accidental loosening when the knob is secured in its desired position of adjustment. The coupling member 24 is also provided with a longitudinal groove 27 which forms a key way operating in connection with an elongated key 28 formed by an inwardly pressed beaded portion which extends into the bore 22 as clearly indicated in Figs. 2 and 3 of the drawing. This construction serves to key the member 24 against rotation while at the same time permits free sliding movement of the member longitudinally of the bore.

After the member 24 has been inserted in the bore, it is also preferred that the end of the spindle be burred or beaded inwardly to form a projecting stop 29 which extends into the bore 22 and thus locks or retains the member 24 against displacement from the bore and establishes a permanent connection therewith.

It will be understood that the key 28 maintains the aperture 26 of the member 24 always in proper alignment or registering position with the aperture 23. In mounting the knob in position, the member 24 may be arranged at any suitable point, preferably adjacent the outer end of the spindle, and the knob is then placed upon the spindle with the aperture 17 arranged directly over the aperture 26. The screw 18 is then placed in position therein, and before tightening the screw, both knobs 15 will be moved into proper position with respect to the plates 13 and on the spindle 20. The loose knob will then be secured in position by the tightening of the screw 18.

The above description is given on the understanding that the other knob of the spindle had been previously attached. With this construction it will appear that very fine adjustments may be provided for the knobs on the spindle so as to fit accurately in the sockets 14 of the plates 13 without any play transversely of the door and simply free enough to provide rotation of the knobs for the actuation of the latch 12.

It will be apparent that in drawing the coupling member 24 into firm engagement with the wall of the bore 22, at both sides of the aperture 23 the roughened or tooth-like outer surface of said member will bite into said walls and positively key and retain the knob against displacement from the spindle. In this connection it will of course be apparent that any type or kind of roughened or tooth-like surface may be provided on the coupling member to perform the functions stated.

It will also be apparent that my invention may be applied to spindles of any desired cross sectional contour, and the bore or passage 22 may also be varied to suit various types of installations. It will be apparent, however, that in any use, and whether or not the knob is provided with a socket 19 corresponding in cross section to the cross section of the shank, the coupling provided will secure or retain the knob against rotary movement on the spindle as well as longitudinal movement thereon.

One of the features of my invention resides in the provision of means for not only retaining the aperture of the coupling in registering alignment with the aperture 23, but also to support the surface of the coupling adjacent said aperture. While in the accompanying drawing, this result is accomplished by employing a coupling member having a cross section substantially conforming with the cross section of the bore or passage 22, it will be apparent that other means will accomplish this same result.

It is also preferred that the apertures 21 be drilled at a slight inclination to the perpendicular so as to produce the same wedge-like action upon the screw in retaining a knob at the end 15 of the spindle having said apertures 21, as is accomplished with the structure shown in Fig. 2.

Having fully described my invention, what I claim as new and desire to secure by Letters Patent, is:

1. An adjustable doorknob mounting of the character described comprising a spindle, at least one end portion of the spindle having an elongated passage arranged longitudinally thereof, one wall of the spindle having an elongated aperture communicating with said passage, a coupling member mounted in the passage for free movement longitudinally thereof, said member having a cross sectional contour substantially corresponding to that of the passage to fit snugly therein, with one surface of the member maintained in position adjacent said aperture, a screw adjustably coupled with said member and extending through the aperture in said spindle for securing a knob in one of a number of positions of adjustment longitudinally of the spindle, and said member having means on the outer surfaces thereof for engaging the wall of said passage when said screw is tightened to permanently retain a knob against movement longitudinally of the spindle.

2. A spindle construction for the adjustable mounting of doorknobs comprising an elongated spindle bar having a solid central portion, at least one end portion of the bar having a longitudinal bore and an aperture extending throughout the major portion of the length of the bore and opening outwardly through the wall of the spindle, a coupling member arranged in and movable longitudinally of the bore, said member having a cross sectional contour substantially corresponding to that of the bore to fit snugly therein, means for keying said member against rotation in the bore in the longitudinal movement thereof, said member having a threaded aperture arranged transversely thereof and registering with the first named aperture and a coupling screw for securing a knob to the spindle, said screw passing through the aperture in said spindle and in threaded engagement with the threaded aperture of said member.

3. A spindle construction for the adjustable mounting of doorknobs comprising an elongated spindle bar, at least one end portion of the bar having a longitudinal bore and an aperture extending throughout the major portion of the length of the bore and opening outwardly through the wall of the spindle, a coupling member arranged in and movable longitudinally of the bore, means for keying said member against rotation in the bore in the longitudinal movement thereof, said member having a threaded aperture arranged transversely thereof and registering with the first named aperture and a coupling screw for securing a knob to the spindle,

- 5 said screw passing through the aperture in said spindle and in threaded engagement with the threaded aperture of said member, and the threaded aperture of said member being arranged at an inclination to a line perpendicular to the surface of said member to provide a wedge-like engagement of the screw to retain the latter against loosening.
- 10 4. A spindle construction for the adjustable mounting of doorknobs comprising an elongated spindle bar, at least one end portion of the bar having a longitudinal bore and an aperture extending throughout the major portion of the length of the bore and opening outwardly through 15 the wall of the spindle, a coupling member arranged in and movable longitudinally of the bore, means for keying said member against rotation in the bore in the longitudinal movement thereof, said member having a threaded aperture arranged transversely thereof and registering with the first named aperture and a coupling screw for securing a knob to the spindle, said screw passing through the aperture in said spindle and in threaded engagement with the threaded aperture of said member, and means keying the coupling member against movement longitudinally of the bore when said member is clamped in position by said screw. 5
- 15 6. A wide range mounting for doorknobs of the character described, comprising an elongated spindle, a member slidably engaging one end portion of the spindle, means for coupling a door-knob with said member, said means being arranged transversely of said knob and member, means keying said member against rotary movement with respect to the spindle, and other means between the spindle and member establishing a firm key-like coupling therebetween to fixedly retain a knob against movement longitudinally 20 of the spindle in one of a number of wide range adjustments of a knob on the spindle through the medium of said coupling means. 20
- 25 7. A wide range mounting for doorknobs of the character described, comprising an elongated spindle, a member slidably engaging one end portion of the spindle, means for coupling a door-knob with said member, said means being arranged transversely of said knob and member, means keying said member against rotary movement with respect to the spindle, other means between the spindle and member establishing a firm key-like coupling therebetween to fixedly retain a knob against movement longitudinally 30 of the spindle in one of a number of wide range adjustments of a knob on the spindle through the medium of said coupling means, and the other end portion of the spindle having spaced threaded apertures for adjustably supporting another knob on the last mentioned end of the spindle. 30
